UNITED STATES PATENT OFFICE.

CLARA C. MOORE, OF JACKSONVILLE, ILLINOIS.

CAKE-COOLER.

1,143,644.

Specification of Letters Patent. Patented June 22, 1915.

Application filed August 13, 1914. Serial No. 856,620.

To all whom it may concern:

Be it known that I, CLARA C. MOORE, a citizen of the United States, residing at Jacksonville, in the county of Morgan and 5 State of Illinois, have invented certain new and useful Improvements in Cake-Coolers, of which the following is a specification.

This invention relates to kitchen and table articles and more specifically to cake 10 coolers.

The object of my invention is to provide a device for cooling a cake when it is turned out of the pan in which it was baked, without making the top crust soggy as it always 15 must be unless the steam is allowed to escape. This is accomplished by providing a raised porous stand under which the air may circulate freely and upon which the cake is laid. A cloth cover is provided to 20 keep the cake from contact with the metal portion of the cooler, and as it is easily attached and detached it may readily be removed and cleaned. This device is simple 25 and durable in construction and efficient in operation.

Other objects of this invention not at this time more particularly enumerated, will be clearly understood from the detailed description and drawings forming a part of 30 this specification.

Furthermore, this invention consists in the novel arrangement and combination of parts more particularly described in the following specification and embodied in the 35 claim appended hereunto and forming a part of this application.

Referring now to the drawings which are merely illustrative of my invention Figure 1 is a perspective of the metal portion of my 40 cake cooler, while Fig. 2 is a view of the cloth cover thereof laid flat. Fig. 3 is a perspective of my device with cloth cover attached. Fig. 4 is a cross-sectional view of the metal portion of the cooler.

45 Referring further to the drawings wherein similar reference characters designate similar parts throughout the respective views, 1 designates a substantial metal frame, with legs 2 formed integral therewith along the edge and preferably at the corners thereof. A plurality of metal strips 50 or relatively heavy wires 3 are spaced apart from one side of the frame to the other, while similarly arranged strips or wires are

interposed between the other sides of the 55 frame and intersecting said first mentioned strips or wires at right angles thereon. The said strips or wires 3 are covered by a fine wire mesh 4, said wire mesh being secured at the sides to frame 1. A cover 5, made preferably of cheese-cloth, is adapted to cover the top of the wire mesh and frame above described. At each corner of said cover a ring 6 is secured, adapted to engage with the legs 2 of the metal rest as shown in Fig. 3 65 of the drawings. The cover may be of substantially the same size as the outer circumference of the frame 1, and as the material used is easily stretched, the rings secured thereto may readily be engaged with the 70 legs of the metal rest by drawing them down singly over the edge of the frame 1 and slipping the ring over the leg. When the last ring is engaged with a leg, the cloth cover is taut and smooth upon the frame. 75

The utility, adaptability, and advantages of my improved form of cake cooler being obviously apparent, it is unnecessary to further enlarge upon the same herein.

Having now described and pointed out 80 the new and useful features of my invention, I do not limit myself to the shape of certain parts where the shape is not essential, nor do I restrict myself to the exact details of construction shown and described, but 85 mean and intend to claim all equivalents and variations thereof not departing in principle from my invention and falling within the purview of the appended claim.

What I claim as my invention and desire to secure by Letters Patent is:

In a device of the kind described, in combination, a rectangular frame, legs formed on the corners of said frame, cross-rods interposed between the sides of said frame, a 95 wire mesh covering said cross-rods and secured upon said frame, a rectangular cloth coextensive in size with said frame, and a plurality of ring members each of which is mounted on said cloth at the corners thereof 100 and are adapted to engage with said legs to hold the cloth taut upon the mesh.

In testimony whereof I affix my signature in presence of two witnesses.

CLARA C. MOORE.

Witnesses:

AINSLIE MOORE,

CHARLES M. JOHNSON.
